UNITED STATES PATENT OFFICE.

MARKOS VASSALAKIS, OF WASHINGTON, DISTRICT OF COLUMBIA.

COMBINED RUDDER AND FENDER.

Specification of Letters Patent.

Patented Mar. 24, 1914.

1,091,027.

Application filed June 9, 1913. Serial No. 772,633.

To all whom it may concern:

Be it known that I, MARKOS VASSALAKIS, a subject of the King of Greece, residing at Washington, in the District of Columbia, have invented certain new and useful Improvements in Combined Rudders and Fenders, of which the following is a specification, reference being had to the accompanying drawings.

10 This invention relates to new and useful improvements in ships and more particularly to a combined rudder and fender for ships and other small craft and my object is to provide a device of this character which 15 is applicable to the bow of the boat to steer the same and simultaneously act as a fender or bumper therefor in case of emergency.

A further object of the invention resides in providing a device composed of a plurality of plate-like sections hinged one to the other and suitably supported from the bow of the boat to fit snugly to the latter and a still further object resides in providing spring means in connection with certain 25 of the plate-like sections to normally retain the same in operative position and, at the same time, act as a buffer at such times as the boat carrying the device collides with other ships or obstructions met in the path thereof.

30 Still another object of the invention resides in providing a means for operating certain of the plate-like sections so that the same may act as a rudder for the ship carrying the same and a still further object resides in providing a device which is simple and durable in construction, inexpensive to manufacture and one which will be very efficient and useful in operation.

40 With these and other objects in view, the invention consists in the novel features of construction, combination and arrangement of parts as will be hereinafter referred to and more particularly pointed out in the specification and claims.

45 In the accompanying drawings forming a part of this application, Figure 1 is a side elevation of my device showing the same applied to use on a large ship. Fig. 2 is a front elevation of the same in its normal position. Fig. 3 is a similar view showing the device disposed to the position that it would, if the boat collided with an obstruction or other ship. Fig. 4 is a horizontal section as seen on line 4-4, Fig. 1. Fig. 5 is a similar view as seen on line 5-5 Fig. 1. Fig. 6

is a side elevation of the inner members of the device showing the plate-like sections and hull of a boat in connection therewith, in dotted lines. Fig. 7 is a perspective view 60 of the plate-like sections of the device removed from the remaining portions thereof and disclosing in dotted lines the position of said sections as they would be when the same collided with an obstruction or ship. Fig. 8 is a fragmentary perspective view of 65 a slightly modified form of the invention. Fig. 9 is a horizontal section through this modified form of the device, taken on a plane just above the springs used in this 70 form of the device. Fig. 10 is a similar view taken on a plane below the plane of Fig. 9 and showing the springs removed. Fig. 11 is a fragmentary side elevation of 75 the device showing parts in section and having certain parts removed. Fig. 12 is a detail perspective view partly in section, of one of the spring members used in this form of the device. Fig. 13 is a horizontal section 80 through the device, showing the manner of hinged supporting the plate-like sections in position in both forms of the device. Fig. 14 is a plan view partly in section of 85 a means for securing the support to the plate-like sections on the ship and also disclosing the means for operating the rudder in both forms of the device. Fig. 15 is a detail section partly in elevation showing a supporting means for the device, as used in both forms thereof. Fig. 16 is a horizontal 90 section as seen on line 16-16, Fig. 1, it being understood that this structure is also used in connection with the modified form. Fig. 17 is a diagrammatic view of the device, as applied to use in its normal position; and Fig. 18 is a similar view showing the device in a position when the same meets with 95 an obstruction in the path of the ship carrying the same.

In describing my invention, I shall refer 100 to the drawings in which similar reference characters designate corresponding parts throughout the several views and in which 1 indicates a ship of any desired character, to the bow of which is applied my improved 105 invention which comprises a combined rudder and fender or bumper therefor. Secured to the bow, at the upper and lower ends thereof, are the bearings 2, in which is mounted to rotate therein a shaft 3, to the 11 upper end of which is connected a cross arm 4 having the ends thereof engaged with the

ends of a steering cable 5. This cable is connected through the usual or any preferred operating means to a pilot wheel 6, whereby said shaft 3 may be turned in either direction, as desired, by the pilot of the ship. To the above referred to shaft 3 is connected the device proper which consists of upper and lower sections A and B, respectively, each of which in turn consists of 10 pairs of hinged together plate-like sections, the pairs of plate-like sections forming the upper section A being hinged to a shaft 8 and the pairs of plate-like sections forming the lower section B being hinged to a shaft 8'. Loosely mounted on the shaft 3, at predetermined points on the upper half thereof, are the pairs of strap hinges 9, said hinges being also suitably connected to the inner faces of the inner plate sections of the upper section A of the device. Pivotally mounted at predetermined points on the lower half of the shaft 3 are the additional strap hinges 10, said latter hinges being also suitably secured to the inner faces of the inner plate-like sections 7 forming the lower section B of the device. This structure is clearly disclosed in Fig. 6 of the drawings. It will thus be seen from this particular structure that the operation of the lower section, as a rudder, is entirely independent of the upper section of the device and the operation of the lower section in one direction or the other on the shaft 3 will not affect the position of said upper section. Also mounted loosely on the upper half of the shaft 3 is a clamping member or the like 11, which carries a pair of arcuate leaf springs 12, the one of which has its ends loosely contacting with the inner face of the one inner plate-like section of the upper section A and the other spring has similar contact with the inner face of the other inner plate-like section 7 of said upper section A. The contact of these springs 12 with the inner plate sections of the pairs of hinged sections 7, is adjacent the shaft 8, thus causing the inner sections of the pairs of plate sections 7, forming the sections A to apparently diverge outwardly and rearwardly. Secured rigidly about centrally of the lower half of the shaft 3, is a clamping member 13 which carries an additional arcuate leaf spring 14, the free ends of which loosely contact with the shaft 8'. The normal tendency of this spring is to force outwardly on the shaft 8', so that the latter will normally align with the shaft 8 of the upper section A and in so doing, the inner pair of plate sections 7 of the lower section B will diverge rearwardly and outwardly, as the similar plates in the upper section A.

Mounted on the deck of the ship 1, immediately adjacent the bow thereof, is a bearing 15, the base of which is provided with a socket 16. The rear wall of the

socket 16, at the upper portion thereof is offset to provide a shoulder 17 and a forwardly bent arm 18 is loosely pivoted between the side faces of said bearing 15. The loose pivot is provided, through the medium of a pin-and-slot connection and the lower end of this arm 18 is adapted to rest against the shoulder 17, above the socket 16. The outer free end of said arm 18 has a chain 19 engaged therewith, which depends between the plate-like sections of my improved device and has branch connections at its lower end, as shown at 20, to be engaged with the inner faces of the inner plate-like sections of said lower section B. This arm supports the lower section B slightly above its bearing, so that said section may be readily operated on the shaft 3 when the latter is partially rotated in either direction. Should the ship meet an obstruction, however, and the arm 18 be forced rearwardly, the lower end of said arm will be relieved of its contact with the shoulder 17 and drop downwardly into the socket 16 to be out of possible engagement with the obstruction met and thus avoid possible destruction of the same.

The outer plate-like sections 7 of the upper and lower sections A and B are provided with tongues or straps 21 which are guided through keepers or the like 22 to rest on angular supporting brackets 23, the latter being secured to the sides of the ship. Thus, in the normal position of the device, the outer hinged plate sections 7 will be retained closely to the sides of the vessel and will be properly supported thereagainst. The vertical portions of the angular brackets 23 have the forward ends thereof bent upon themselves, as shown at 24 to provide shoulders or the like against which the free ends of said straps or tongues may rest when the outer plate-like sections 7 are drawn forwardly at the time the device meets an obstruction. This structure is clearly shown in Fig. 16 of the drawings and in dotted lines in this figure, is shown the position of the tongues or straps in engagement with the aforesaid shoulders on the angular brackets.

The shaft 3 has a clamping ring 18' mounted thereon which is provided with a pair of arms 19' extending therefrom in opposite directions. These arms 19' are connected by the flexible connections 20' to the inner faces of the inner plate sections 7 of the lower section B of the device. These connections between the shaft 3 and the lower section B, permit an operation of this lower section upon the turning of said shaft 3.

From the above description, it will be appreciated that the normal position of the parts is such as to dispose the upper and lower sections A and B of the device in substantial alinement, one with the other, the inner hinged plate sections 7 converging for-

wardly and the outer plate sections clinging closely to the sides of the vessel, adjacent the bow. It will also be understood that this position of the device is a normal one, under tension of the springs. It will be seen, however, that the lower section B forms a rudder for the device and may be operated directly from the shaft 3, it being understood that the latter shaft may be operated from the pilot wheel 6, from the means heretofore described and shown in the drawings. The operation of this lower section B, or rudder of the device is entirely independent of the operation of the upper section A and the oscillation of said shaft 3, in one direction or the other will not affect the parts in connection with the upper section A, inasmuch as said latter parts are loosely mounted on said shaft 3. It will be seen, however, that in case the device meets an obstruction, both the upper and lower sections A and B will act as fenders or bumpers for the device and the tapering or converging position of the plate-like sections of said sections A and B will yield against the tension of the springs 12 and 14 to assume a position as shown in Figs. 3 and 18 of the drawings. In such position, the outer plate-like sections 7 of the device will be turned somewhat forwardly and the waves washing inwardly against the sides of the ship will force the same inwardly and thus the tongues or straps 21 will assume the position as shown in dotted lines in Fig. 16, *i. e.*, in engagement with the shoulder 24. Thus a stop is provided, but as soon as the contact of the obstruction with the bow of the boat is released, the springs 12 and 14 will again act to force outwardly on the shafts 8 and 8', whereby the device may assume its normal and initial position. This position is clearly shown in Figs. 2 and 17 of the drawings.

In Figs. 8 to 12 inclusive, I have shown a slightly modified form of the invention and in this form, a shaft 25 is provided and suitably mounted in bearings 26 which are adapted to be secured to the bow of a boat at its upper and lower ends. The upper end of this shaft 25 is adapted to be connected with the steering mechanism, as described in the first mentioned form and pivotally mounted on said shaft, adjacent its upper and lower ends, are the strap hinges 27. These strap hinges are adapted to support from the shaft 25, the modified form of my device proper, which consists of pairs of hinged together plate sections 28, each pair being in turn hinged to a shaft 29. This device is particularly applicable to small craft and the plate sections 28 are adapted to extend for substantially the full height of the bow of the boat and the outer ends of the strap hinges 27 are pivotally engaged with the inner faces of the inner plate sections 28, which are hinged directly on the shaft 29.

The device proper is, therefore, suitably supported from the shaft 25.

Mounted on the shaft 25, at a predetermined point thereon, is a ring member or the like 30 which has a pair of arms 31 formed thereon, projecting in opposite directions and connected to the free ends of these arms are the chains 32, which also engage hook members or the like on the inner faces of the inner plate sections 28. With the turning of the shaft 25, it is obvious that the inner plate sections 28 will also be turned therewith, in view of the flexible connections 32.

Secured to the shaft 25 just below the arms 31, is a clamping member 33 which retains in position, a pair of arcuate leaf springs 34. The free ends of these leaf springs contact loosely with the inner faces of the inner plate sections 28, as do the springs 12 of the first mentioned form and force said inner plate sections forwardly and act as buffers or bumpers for said plate sections, when the latter are forced inwardly. An additional and central arcuate leaf spring 35 is also carried by the clamping member 33 and the free ends thereof are secured to the shaft 29. This leaf spring forces the apex of the member forwardly and normally retains said member in such a position as to dispose the inner plate sections to a forwardly converging position. In this form of the device, the means for retaining the outer plate sections to the sides of the boat are the same as in the first mentioned form. In this modified form of the device, it will be seen that the complete device forms a combined rudder and bumper or fender for the boat and the turning of the shaft 25, in one direction or the other will positively turn the complete device in the desired direction. At the same time, should the boat, having this device applied thereto, come in contact with a ship or other obstruction, the forward portion of the device will be compressed against the tension of the springs 34 and 35 and the shock will be retarded and partially absorbed thereby and complete injury to the bow of the boat avoided.

From the foregoing description of the construction of my improved device, the operation thereof will be readily understood and it will be seen that I have provided a device which will positively carry out the purpose for which the same is designed.

It will further be seen that the device is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to without departing from the spirit

or sacrificing any of the principles of the invention.

Having thus described this invention, what is claimed is:—

5. 1. A device of the class described comprising a collapsible frame formed of an upper and lower section, each section being composed of a plurality of plates hinged one to the other, means to operatively support the sections of said frame on the bow of a boat, means in connection with portions of the sections of said frame to yieldingly dispose the same in a predetermined position, and means for actuating one of said sections independent of the other, whereby to form a rudder for the boat.
10. 2. A device of the class described comprising a collapsible frame formed of a plurality of plate-like sections hinged one to the other, said frame being divided into an upper and lower section operable independent of one another, means to operatively support the sections of said frame on the bow of a boat, spring means in connection with certain of the plate-like sections of the upper and lower sections of said collapsible frame to dispose the same in forwardly converging position, and means for operating the lower section of the collapsible frame independent 25 of the upper section thereof.
20. 3. A device of the class described comprising a collapsible frame formed of an upper and lower section, each composed of a plurality of plates hinged one to the other, means for operatively supporting said frame on the bow of a boat, spring means in connection with the similar plates of the upper section, means in connection with the outer hinged plates of said upper and lower sections to movably support the same against the sides of the boat, immediately adjacent the bow thereof, and means to actuate the lower section of the frame independently of the upper section thereof, whereby to form a 30 rudder for the boat.
35. 30. 3. A device of the class described comprising a collapsible frame formed of an upper and lower section, each composed of a plurality of plates hinged one to the other, means for operatively supporting said frame on the bow of a boat, spring means in connection with the inner hinged plates of the upper and lower sections to dispose the same in forwardly converging position, means to movably retain the outer hinged plates to the sides of the boat, immediately adjacent the bow, and means for actuating the lower section of the frame independent of the upper section thereof, whereby to form a 40 rudder for the boat.

4. A device of the class described comprising a collapsible frame formed of an upper and lower section, each composed of a plurality of plates hinged one to the other, means for operatively supporting the sections of said frame on the bow of a boat, spring means in connection with the inner hinged plates of the upper section to retain the same in forward converging position, additional spring means in connection with the lower section to normally dispose the inner plate sections of the latter in alining position with the similar plates of the upper section, means in connection with the outer hinged plates of said upper and lower sections to movably support the same against the sides of the boat, immediately adjacent the bow thereof, and means to actuate the lower section of the frame independently of the upper section thereof, whereby to form a 45 rudder for the boat.

45. 5. A device of the class described comprising a collapsible frame formed of an upper and lower section, each composed of a plurality of plates hinged one to the other, means for operatively supporting the sections of said frame on the bow of a boat, spring means in connection with the inner hinged plates of the upper section to retain the same in forward converging position, additional spring means in connection with the lower section to normally dispose the inner plate sections of the latter in alining position with the similar plates of the upper section, means in connection with the outer hinged plates of said upper and lower sections to movably support the same against the sides of the boat, immediately adjacent the bow thereof, and means to actuate the lower section of the frame independently of the upper section thereof, whereby to form a 50 rudder for the boat.

55. In testimony whereof I hereunto affix my signature in the presence of two witnesses.

MARKOS VASSALAKIS.
